United States Patent

Des. 239,631
Patented Apr. 20, 1976

239,631

LIGHTER

Gilles Lauri, 34 Allee Marceau, Livry-Gargan,
Seine Saint-Denis, France

Filed Dec. 26, 1974, Ser. No. 536,338

Claims priority, application France July 25, 1974

Term of patent 14 years

Int. Cl. D27—05

U.S. Cl. D27—42

FIG. 1 is a perspective view of a lighter showing my new design;

FIG. 2 is a top plan view thereof on an enlarged scale;

FIG. 3 is a rear view thereof on an enlarged scale;

FIG. 4 is a right side view thereof on an enlarged scale;

FIG. 5 is a left side view thereof on an enlarged scale; and

FIG. 6 is a bottom plan view thereof on an enlarged scale.

The front is shown in FIG. 1 and is merely a mirror image of the rear.

I claim:

The ornamental design for a lighter, substantially as shown and described.
